CLAIM

The ornamental design for a pendant as shown and described.

DESCRIPTION

FIG. 1 is a top plan view of a first embodiment of a pendant, showing my new design, the bottom plan view being a mirror image thereof;

FIG. 2 is a top plan view thereof, showing the pendant of FIG. 1 in an open position;

FIG. 3 is a bottom plan view thereof, showing the pendant of FIG. 1 in an open position;

FIG. 4 is a top perspective view thereof, showing the pendant of FIG. 1 in a closed position;

FIG. 5 is a top perspective view thereof, showing the pendant of FIG. 1 in an open position;

FIG. 6 is a top plan view of a second embodiment of the pendant, showing my new design in a partially open position;

FIG. 7 is a top plan view thereof, showing the pendant of FIG. 6 in an open position;

FIG. 8 is a bottom plan view thereof, showing the pendant of FIG. 6 in an open position;

FIG. 9 is a top perspective view thereof, showing the pendant of FIG. 6 in a partially open position; and,

FIG. 10 is a top perspective view thereof, showing the pendant of FIG. 6 in an open position.

The broken lines immediately adjacent to the shaded areas in the drawings represent portions of the pendant and form no part of the claimed design. The other broken lines represent environmental subject matter only and form no part of the claimed design.
